UNITED STATES PATENT OFFICE

WILLIAM E. LUNDGREN, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

RACK FOR FINGERS OF DOBBY LOOMS

Application filed August 2, 1929. Serial No. 383,071.

This invention relates to improvements in the racks for dobbies fingers and it is the general object of the invention to provide an improved rack or separating device which 5 shall be easily manufactured, comparatively silent in operation, and efficiently held in position with respect to the dobbey frame.

Loom dobbies employ in their construction a plurality of flat fingers which are movable 10 in vertical planes under the action of the pattern chain. These fingers control hooks which in turn are operatively connected to the several harnesses of the loom, and oppositely reciprocating lifted knives cooperate 15 with such hooks as are down to lift the corresponding harnesses. The pattern chain usually employs wooden bars with upstanding pegs, and it is necessary to provide some form of guide to hold the fingers in proper 20 alignment with the pegs. It is an important object of my present invention to provide a non-metallic strip of material which has secured thereto a plurality of spaced parallel wires or dents which define a rack to 25 guide the fingers, the bar being held in position by extensions which project from certain of the wires or dents.

It is a further object of my invention to 30 form the rack of a plurality of wires certain of which are somewhat larger, either in diameter or length than the other wires, the larger wires being driven into a supporting structure and acting to hold the bar and the remaining smaller wires in proper position. I 35 find that in making the holding wires somewhat larger their removal is facilitated when it is desired to replace a new rack.

In order to provide a durable construction 40 I employ a metallic holder which is braced to the dobbey frame but I avoid contact between the fingers and this metallic support by means of a wooden bar or holder for the reed wires or dents, thereby avoiding wear of parts more 45 expensive than wood and also introducing a silencer which effects more quiet operation of the dobbey.

With these and other objects in view which 50 will appear as the description proceeds, my invention resides in the combination and ar-

angement of parts hereinafter described and set forth in the claims.

In the accompanying drawings, wherein two forms of the inventions are shown,

Fig. 1 is a side elevation of a dobbey incorporating the preferred form of my present invention, 55

Fig. 2 is a side elevation taken in the direction of arrow 2, Fig. 1,

Fig. 3 is an enlarged vertical section taken 60 on line 3-3 of Fig. 2,

Fig. 4 is a top plan view taken in the direction of arrow 4, Fig. 2 showing the rack and its support, and

Fig. 5 is a view similar to a portion of Fig. 65 2 but showing the modified form of construction wherein the holding pins project above the other pins.

Referring to Fig. 1, I have shown a frame F with a rocker arm 10 pivoted as at 11 and having connection with a depending driving rod 12 which may be raised every alternate pick of the loom and depressed on intervening picks. Upper and lower lifting knives 13 and 14 are attached by means of 70 connectors 15 to the upper and lower arms 16 and 17, respectively, of the rocker arm 10. These knives cooperate with hooks 18 and 19, respectively, which are attached by means of a jack indicated herein at 20 to the 75 harnesses not shown.

The lower hooks are governed by means of fingers 21 which have upturned ends 22 for direct engagement with said hooks. The upper hooks 18 are controlled by lifter wires 23 which are operatively connected to other fingers 24. Every alternate finger will be of the type designated at 21, while the intervening fingers will be of the other type. A pattern surface 25 on a pattern cylinder 26 90 controls the rising and falling of the fingers 21 and 24 and through connections described determine the position of the hooks relatively to the knives. The matter thus far described is of common construction and forms no part 95 of my present invention, being made and operating in the usual and well-known manner.

In carrying the preferred form of my invention into effect I provide an improved 100

guide for the right hand ends of the fingers 21 and 24 as viewed in Fig. 1. This guide comprises a support 30 formed preferably of metal and has upturned wings 31 and 32 which are located, respectively, at the right and left hand ends of the support. Bolts 33 secure the wings of the frame of the dobby F. Extending between the wings 31 and 32 and lying on a horizontal body 34 of the support is a bar 35 made preferably of wood. This bar may be proportioned as set forth in Fig. 3 and substantially fills the space between the wings 31 and 32. The upper surface 36 of the wooden bar has extending upwardly therefrom a plurality of relatively small parallel spaced wires or rack dents 37 between which extend the ends of the fingers. As shown particularly in Fig. 2 the wires 37 preferably extend only part way into the wooden bar 35.

In order to hold the bar to the support I provide other wires 38 which are in alignment with the smaller wires as set forth in Fig. 4 but may be of larger diameter. These larger wires extend entirely through the bar 35 and into the body 34 of the support, and are held frictionally in the support, being driven into position. The larger wires 38 cooperate with the adjacent smaller bars to space the fingers 30 lying on either side thereof.

I find that the larger diameter of the wires 38 facilitates their removal. When it is desirable to replace bar 35 any suitable tools, such as for instance a pair of pliers, may be employed to grip opposite sides of the wires. Because of the fact that the latter are larger than the wires 37 the smaller wires will not be pulled out of position.

I do not wish to be limited to the use of the larger wire, however, as I may employ retaining wires 39 which extend above the shorter wires 40 as shown in a modification set forth in Fig. 5. So far as this feature of my invention is concerned it is sufficient if the retaining wires 38 or 39 extend beyond the zone occupied by the wires 37 or 40 so as to present a portion which may be engaged by a moving tool without disturbing the setting of the other wires.

From the foregoing it will be seen that I have provided an improved form of guide and dobby finger wherein a non-metallic bar, preferably though not necessarily wood, has inserted therein finger spacing wires certain of which extend entirely through the bar and into a rigid, preferably metallic part of the dobby structure. Furthermore, it will be noted that the fingers which hold the bar in position are so proportioned as to extend beyond the zone occupied by the remaining fingers, thereby permitting removal of said holding fingers without disturbing the other fingers.

Having thus described my invention it will be seen that changes and modifications may

be made therein by those skilled in the art without departing from the spirit and scope of the invention and I do not wish to be limited to the details herein disclosed, but what I claim is:

1. In a loom dobby having fingers, a support under the fingers, a wooden bar on the support, and wires projecting upwardly from the bar to space the fingers, certain of said wires extending through the bar and into the support to hold said bar in position on the support. 70

2. In a loom dobby having fingers, a supporting member in fixed position relatively to the dobby, a non-metallic bar extending under the fingers, wires extending upwardly from the bar to space the fingers, certain of said wires extending through the bar and into the member to hold the bar in position on the member. 80

3. In a loom dobby having fingers, a supporting member fixed with respect to the dobby, a bar separate from but deriving support from the member, a plurality of wires carried by and projecting from said bar to space the wires, certain of said wires extending through the bar and into the member to hold the bar in position on the member. 85

4. In a loom dobby having fingers, a supporting member fixed with respect to the dobby, a bar separate from but deriving support from the member, a plurality of wires carried by and projecting from said bar to space the wires, certain of said wires extending through the bar and into the member to hold the bar in position on the member, said wires which extend into the member being larger than the other wires to facilitate removal thereof. 90

5. In a loom dobby having fingers, a supporting member fixed with respect to the dobby, a bar separate from but deriving support from the member, a plurality of wires carried by and projecting from said bar to space the wires, certain of said wires extending through the bar and into the member to hold the bar in position on the member, said wires which extend into the member projecting beyond the zone occupied by the other wires to facilitate removal thereof. 105

In testimony whereof I have hereunto affixed my signature.

WILLIAM E. LUNDGREN.
